UNITED STATES PATENT OFFICE.

HUGH WILLIAMSON KELLY, OF TRENTON, NEW JERSEY.

TRACK-TORPEDO.

Specification of Letters Patent.

Patented Dec. 4, 1917.

1,249,113.

Application filed October 30, 1916. Serial No. 128,456.

To all whom it may concern:

Be it known that I, HUGH WILLIAMSON KELLY, a citizen of the United States, and a resident of Trenton, Mercer county, New Jersey, have invented certain Improvements in Track-Torpedoes, of which the following is a specification.

My invention relates to rubber torpedoes; that is to say, railroad or track torpedoes 10 in which a body of detonating material is carried or supported by or inclosed in a shell or casing of rubber or rubber-containing material, and having means whereby it may be attached or secured to the head of a 15 rail.

Various forms of rubber torpedoes form the subject of my prior applications for patents, filed December 3, 1915, December 24, 1915, April 5, 1916, and May 27, 1916, Serial 20 Nos. 64,869; 68,545; 89,075, and 100,259, respectively.

One object of my present invention is to facilitate the formation of torpedoes of this type while reducing the cost of the 25 same, and to increase the factor of safety in the use of torpedoes of this type. My invention further includes a torpedo which may comprise a portion to embrace the head of a rail, made of rubber or rubber-containing material, with which may be combined 30 a shell or casing of other material containing the detonating charge; which shell or casing is arranged to interlock or interengage with cups or projections carried by 35 the rail-engaging portion.

As a further modification, in lieu of providing a strap or cross-piece carrying the rail-engaging lugs as well as recesses or projections for engaging the container for the 40 load of detonating material, I may provide a strap or cross-piece having rail-engaging lugs of such a character as to be insertible in the container for the charge of detonating material; such strap being securely held 45 thereto by the insertion of the charge. In such instance the holder or casing for the charge may be of any desired shape in cross section; it being necessary only to provide a size that will receive the strap connecting 50 the rail-engaging lugs as well as the detonating charge. In any instance, the ends of the casing receiving the detonating charge will be suitably sealed after the charge is inserted.

55 A still further modification consists in

providing independent rail-engaging lugs with projections designed to fit into the ends of charge-holding members, which may comprise a shell of rubber or suitable composition, or even of paper, properly water-proofed. In some instances, it may be possible to provide the rail-engaging lugs with metal projections to assist in holding the torpedo to the head of a rail.

These and other features of my invention 60 are more fully described hereinafter, reference being had to the accompanying drawings, in which:

Fig. 1, is a perspective view illustrating the detached parts of one form of torpedo 70 within the scope of my invention.

Fig. 2, is a longitudinal sectional view of a complete torpedo made up of the parts 75 illustrated in Fig. 1, in position upon the head of a rail.

Fig. 3, is a cross-sectional view on the line III—III, Fig. 2.

Fig. 4, is a perspective view similar to Fig. 1, showing the detached parts of another form of torpedo within the scope of 80 my invention.

Fig. 5, is a longitudinal sectional view of a complete torpedo made up of the parts 85 illustrated in Fig. 4, in position upon the head of a rail.

Fig. 6, is a cross-sectional view on the line VI—VI, Fig. 4.

Fig. 7, is a sectional view showing a construction in which the detonating charge-carrying portion is provided with a continuous web or strip connected to the ends thereof to overlie the shell or carrier for the detonating material and serving additionally to retain the same in place.

Fig. 8, is a sectional elevation of another 90 form of torpedo within the scope of my invention; the ends of the web of the rail-engaging portion having wedge-shaped lugs to engage the ends of a container for the detonating material.

Figs. 9 and 10, are cross-sectional views 95 of the torpedoes shown in Figs. 7 and 8.

Fig. 11, illustrates the detached parts of another form of torpedo within the scope of 105 my invention, in which the rail-engaging lug-carrying strap is insertible in the container for the detonating material.

Fig. 12, is a longitudinal sectional view 110 illustrating a complete torpedo made up of the parts illustrated in Fig. 11.

Fig. 13, is a cross sectional view on the line XIII—XIII, Fig. 12.

Fig. 14, is a similar sectional view illustrating a modified form of container for the detonating material.

Fig. 15, is a perspective view of a rail-engaging lug adapted for coöperative engagement with a suitable container for a detonating charge and forming with said container, and a similar rail-engaging-lug member at the opposite end thereof, a complete torpedo.

Fig. 16, is a view in section of a modified form of member for engagement with a detonating charge container, of the type shown in Fig. 15.

Fig. 17, is a longitudinal sectional view of a finished torpedo made up of rail-engaging-lug members of the type shown in Fig. 15, and a container for detonating material disposed between the same, and

Fig. 18, is a view of a die press showing the manner in which the rubber or rubber-containing parts in the various forms of the several torpedoes forming the subject of my invention may be extruded through a suitable die and subsequently cut into sections of the desired size, shape and character for coöperative engagement with the shells or casings receiving the detonating material.

In Figs. 1, 2 and 3, of the drawings, I have illustrated a member or carrier for a body of detonating material, comprising a cross-strip or band 1 provided at its ends with ears or upstanding projections 2, and below the same, rail-engaging members 3; the latter being preferably corrugated, as indicated at 4, to increase their frictional engagement with a rail-head. The upstanding ears 2 may be recessed as indicated at 5, to receive the ends of a container for a detonating charge; the container, shown in the present instance as tubular, being indicated at 6, and receiving a charge of detonating material, indicated at 7 in the sectional view. The container may be cemented to the web or strip 1 and to the sockets or recesses 5 which receive its ends by any suitable cementing material available for the purpose, and when such cement is dry, the torpedo is ready for use.

The containers 6 may be made of any suitable material, although they are preferably made of a rubber or rubber-containing body which may be extruded from a die press while the material is in a plastic state, or they may be specially formed by other means, and may comprise a shell of rubber or of material other than rubber or rubber-containing material, such for instance as pasteboard, paper, fabric or like. In the latter instances the material employed is of a waterproof nature or is waterproofed before use.

In lieu of providing the support or car-

rier for the detonating material with recesses in its upstanding ears or shoulders, the latter may be arranged as shown at 2^a in Figs. 4, 5 and 6, and provided with inwardly projecting lugs 10 for engagement with recesses 11 provided in the ends of the shells or casings 6^a, adapted to receive charges of detonating material.

Another arrangement or modification, shown in longitudinal section, Fig. 7, and in cross section, Fig. 9, consists in providing a continuous strip 12 connecting the tops of the upstanding ears or projections 2^b, which strip is designed to overlie the container 6^b for the detonating material; the ends of the latter engaging lugs 10^a on the inner faces of the ears 2^b.

To assist in retaining the detonating charge containers in place, the ears 2^c of the structure shown in longitudinal section, Fig. 8, and in cross section, Fig. 10, may have its coöperating lugs 10^b dovetail in shape, so as to wedge in the end of the detonating charge container 6^c.

A further modification of my invention is shown in Figs. 11, 12 and 13, in which I have shown a strap 1^a carrying rail-engaging lugs 3^a, which strap is adapted for insertion in the container 6^d, as clearly shown in the sectional views, Figs. 12 and 13; such arrangement bringing the lugs 3^a in proper position for engagement with the head of a rail, in the manner illustrated with respect to the other forms of torpedoes shown. The container 6^d for the detonating charge is shown in Fig. 11 as of cylindrical form, but it will be understood that containers having a different cross section may be employed, and in Fig. 14, I have shown a container 6^e adapted to receive the lug-carrying strap 1^a or band having a cross section substantially in the form of a section of a truncated cone.

In finishing a torpedo of this type, the ends of the container will be brought down and sealed to the strap 1^a carrying the lugs 3^a, as illustrated in Fig. 12.

In Fig. 15, I have shown a structure comprising a rail-engaging lug 3^b formed continuously with an upstanding ear or member 2^d having an inwardly projecting lug 10^c which, when employed in pairs in connection with a detonating charge container, such for instance as indicated at 6^f in Fig. 17, forms a complete torpedo. In this construction, any integral connection between the respective rail-engaging lugs is omitted, and the detonating charge container is depended upon to afford the desired connection and impart to the torpedo that degree of rigidity or stiffness necessary in order that it may be properly secured in the usual manner to the head of a rail.

In Fig. 16, I have shown another member capable of use in the manner illustrated with reference to the structure shown in Fig. 15. 130

In this structure, which may be made of rubber or rubber-containing material, or any other suitable material and comprises an ear 2^e with an inwardly projecting lug 10^d, a 5 metallic piece 15 is combined, preferably of lead, which may form a rail-engaging member designed to hold the finished structure to the head of a rail.

The rail-engaging-lug-carrying portions 10 of the several forms of torpedoes illustrated in Figs. 4, 5, 7, 8, 11, 12, 15 and 16, when made of a plastic body such as rubber or rubber-containing material, may be extruded through dies from presses of usual 15 form well known in the rubber art, in the manner illustrated in Fig. 18, which shows the extrusion of a strip from which members such as illustrated in Fig. 4, may be cut; the extruded body or strip being separated 20 into sections of desired size by suitably disposed cutting means arranged to operate at regular intervals, thereby providing carrier sections of the desired size and form to be subsequently connected with the containers 25 for the charges of detonating material to form the finished torpedoes. These sections of rubber or rubber-containing material may be cured in any approved manner, and the rail-head-engaging lugs 3, 3^a, 3^b, etc., may 30 be shaped by rounding the corners of the same, although this shaping operation is not essential to the construction or proper operation of the torpedo.

In speaking of the carrier structure or the 35 container for the detonating material as made of rubber, it will be understood, of course, that what is meant is a rubber-containing material, the portion of rubber in which may be relatively small. The object 40 is to provide a relatively flexible structure suitable for the purpose and one that will be non-flying and therefore not dangerous under the explosion of the detonating charge. The connection between the rail-engaging lugs and the strip 1, 1^a, &c., to 45 which they are attached may be of a relatively better grade of material than said strip so as to insure the resiliency required of these lugs and at the same time the desired tension when they are placed in the 50 rail-engaging position.

I claim:

1. A track torpedo comprising upstanding ears or projections of non-metallic elastic material and depending rail-engaging lugs, in combination with a container for detonating material interposed between and supported by said upstanding ears.

2. A track torpedo comprising upstanding ears or projections of non-metallic elastic material and depending rail-engaging members of different material carried by said ears, in combination with a container for detonating material interposed between 65 and supported by said upstanding ears.

3. A track torpedo comprising a pair of upstanding ears or projections of non-metallic elastic material having rail-engaging lugs depending therefrom, in combination with a body of detonating material confined 70 between and supported by the upstanding ears or projections.

4. A track torpedo comprising a pair of members each having upstanding ears or projections of non-metallic elastic material 75 and rail-engaging lugs depending therefrom, in combination with a non-metallic shell or casing confined between the upstanding ears or projections, and a body of detonating material disposed within said shell or 80 casing.

5. A track torpedo comprising molded sections of material providing upstanding ears and depending rail-engaging lugs integral therewith, said upstanding ears having 85 inwardly projecting lugs, and a container for detonating material interposed between said ears and interconnecting with the lugs carried by the same.

6. A track torpedo comprising a strip 90 of material having depending rail-gripping lugs, in combination with a container for detonating material operatively connected with said strip and held in place under tension.

7. A track torpedo comprising a strip 95 of material having rail-gripping lugs, in combination with a body of detonating material operatively connected with said strip and held in place under tension.

8. A track torpedo comprising a strip of material having upstanding ears or projections and depending rail-gripping lugs, in combination with a container for detonating material interposed between and supported 105 by said upstanding ears; said container being held in place under tension.

9. A track torpedo comprising a strip of non-metallic elastic material having upstanding ears or lugs surmounting the same 110 and rail-engaging lugs depending therefrom, in combination with a body of detonating material confined between the upstanding ears or projections.

10. A track torpedo comprising a section 115 of non-metallic elastic material having upstanding ears or projections surmounting the same at its ends and rail-engaging lugs depending therefrom, in combination with a shell or casing confined between the upstanding ears or projections, and a body of detonating material disposed within said shell or casing.

11. A track torpedo comprising a strip 120 of non-metallic elastic material having upstanding ears or projections and depending rail-engaging lugs, in combination with a container interposed between said upstanding ears, and a body of detonating material disposed in said container.

12. A track torpedo comprising a molded section of material providing upstanding ears and depending rail-engaging lugs integral therewith, said upstanding ears having inwardly projecting lugs, and a container for detonating material interposed between said ears and interconnecting with the lugs carried by the same.

13. A track torpedo comprising a molded section of material providing upstanding ears and depending rail-engaging lugs integral therewith, said upstanding ears having inwardly disposed projections dovetail in shape, and a container for detonating material interposed between said ears and interconnecting with the dovetail lugs carried by the same.

14. A track torpedo comprising a pair of members each having upstanding ears with dovetail projections and rail-engaging lugs depending therefrom, in combination with a shell or casing confined between the upstanding ears and engaging the dovetail pro-

jections, and a body of detonating material disposed within said shell or casing.

15. A track torpedo comprising a strip of non-metallic elastic material having integral rail-gripping lugs, in combination with a body of detonating material operatively connected with said strip and held in place under tension.

16. A track torpedo comprising a strip of non-metallic elastic material having integral depending rail-gripping lugs, in combination with a container for detonating material operatively connected with said strip and held in place under tension.

17. A track torpedo comprising a strip of non-metallic elastic material having upstanding ears or projections and integral depending rail-gripping lugs, in combination with a container for detonating material interposed between and supported by said upstanding ears; said container being held in place under tension.

HUGH WILLIAMSON KELLY.
